UNITED STATES PATENT OFFICE.

GERALD DEAKIN, OF ANTWERP, BELGIUM, ASSIGNOR TO WESTERN ELECTRIC COMPANY, INCORPORATED, OF NEW YORK, N. Y., A CORPORATION OF NEW YORK.

TELEPHONE SYSTEM.

Application filed December 31, 1924, Serial No. 758,981, and in Great Britain February 12, 1924.

This invention relates to telephone systems and more particularly to systems in which calls are extended from a manual exchange under the control of an operator to an automatic exchange.

It is the object of this invention to provide an electrical control system for trunking between manual and automatic telephone exchanges in which the work devolving upon the manual operator is reduced to a minimum consistent with quick and efficient service. This object is attained by the provision of jacks for each automatic office and a link which is actuated by the insertion of a plug in said jack to associate parts of said link with the terminals of the jack selected and associate an idle trunk to a particular exchange with said jack terminals.

Telephone traffic between offices in some exchange areas is handled entirely by operators. The call is transmitted from the subscriber to an A operator who in turn transmits the wanted number to a B operator over a call wire, and the B operator assigns a trunk to the A operator who inserts a plug in a jack associated with said trunk. This arrangement has disadvantages in that the number is sometimes misunderstood by the B operator and a telephone connection to the wrong subscriber is the result. Other circuit arrangements have been invented for selecting trunks to distant offices with automatic apparatus. These, however, are quite elaborate and costly.

In carrying the present invention into effect each automatic exchange to which calls are extended is represented at the local manual exchange in each operator's position by a jack or jacks. Associated with each set of jacks is a group of connecting units, each unit comprising a jack finder, a trunk or junction finder and a sender finder. Switches are provided in each unit for the purpose indicated by their designations. Each A operator's position is equipped with a ten-button key-set with proper designations in order that the operator may select the desired line by operating certain ones of the keys.

A feature of this invention resides in the use of an improved electric control system for trunking between manual and automatic telephone exchanges in which a trunk to a

particular office is automatically connected to a jack selected by the manual operator.

Other features of the invention will be apparent from the following description taken in connection with the accompanying drawings.

While the invention has been disclosed as particularly adapted for trunking between manual and machine switching offices, it will be apparent, however, from the following description that the invention has a wider utility and by slight modification it could be adapted for other types of equipment.

The invention will be more fully understood from the following description taken in connection with the accompanying drawings in which Fig. 1 illustrates a schematic layout of the system in accordance with this invention.

Fig. 2 shows a connecting or link circuit comprising a jack finder switch, junction or trunk finder switch and a sender finder switch, the purposes of which will be hereinafter more fully described.

Fig. 3 illustrates a junction or trunk circuit extending from the manual exchanges to the apparatus of an automatic exchange diagrammatically shown.

Figs. 4 and 5 illustrate the circuit and apparatus of a register sender which is set in accordance with the operation of keys shown in the lower part of Fig. 2. The automatic switches in a distant exchange are controlled in accordance with the setting of this sender.

At the manual exchange each A operator's position is equipped with a number of jacks the same as jack 207. This position is also provided with a common key-set indicated in the lower portion of Fig. 2 which may be connected to any connecting circuit or link having access to this position.

Each connection or link circuit consists of a jack finder switch 103, a junction or trunk finder switch 105 and a sender finder switch 104 connected together in the manner indicated in Fig. 1. These switches may be of any well known type as, for example, the well known step-by-step switch used in automatic telephone systems. The key-set illustrated at the lower part of Fig. 2 consists of a set of ten keys numbered 1 to 10, the operation of each key connecting heavy

or light positive or negative battery to the apparatus of the sender. The automatic exchange illustrated diagrammatically in Fig. 3 may be of any well known type as, for example, the revertive impulse type in which impulses are sent back to the sender during the operation of the automatic switches thereof.

The sender circuit illustrated in Fig. 4 consists of a number of relays which are adapted to be discriminately operated in accordance with the keys depressed to cause the register or digit switches RS-1, RS-2, RS-3 and RS-4 of Fig. 5 to take up definite positions. The digit switches may be of any well known construction and as indicated, each comprises a pair of brushes, each brush moving over a bank of contacts by the operation of a stepping magnet which is provided with means for interrupting its own circuit.

Detailed description.

A subscriber of a manual exchange who desires a connection with a subscriber of an automatic exchange informs the operator accordingly. The operator, whose position is indicated at the left of Fig. 1, inserts the calling plug of one of the position cord circuits into an idle jack 100 of the desired exchange. The jack finder 103 of an idle connecting circuit thereupon propels its brush assembly until it is associated with jack 100. In a like manner brush 108 is propelled to select an idle sender. Lamp 120 is associated with the operator's key-set and is lighted to indicate to the operator that switch 103 is associated with said key-set. The operator now actuates certain of the keys in the key-set to transmit the digits of the wanted number to the apparatus of the sender. When the final digit key is actuated, the trunk finder 105 operates to select the idle trunk leading to the distant automatic exchange. The establishment of the call is now under the control of the sender and the operator is free to answer other subscribers' calls at her position. Automatic selector switches such as shown schematically in Fig. 3 are set in accordance with the operation of the sender and the called line is connected to the calling subscriber. The operator supervises the call in the usual manner and the end of a conversation is indicated to the operator by the circuit supervisory lamps in the switchboard position.

Let it be assumed that a call is received at the "A" operator's position and that the call is answered by the A operator in the usual manner of inserting the answering plug of the cord circuit into the answering jack. The wanted number is obtained by the operator from the subscriber and the calling cord 261 is inserted in trunk jack

207. The insertion of plug 261 into jack 207 establishes a circuit from ground through the upper contact of jack 207, left inner contact of relay 206, resistance 205 to terminal 204. A circuit is also established to energize the start relay 208 from grounded battery through its winding, resistance 209 and thence to ground at the upper contact of jack 207. The operation of relay 208 establishes an obvious circuit to energize relay 239. The operation of relay 239 establishes a circuit to energize magnet 210 from ground through the right inner contact of relay 239, windings of magnet 210 to grounded battery through the normal contact of relay 211 and the right outer contact of relay 246. Magnet 210 is energized over the circuit traced, to rotate brushes Nos. 212 to 215, inclusive, of the jack finder switch over the contacts in its bank. In a like manner other magnets the same as 210 in a group of links are energized by the operation of relay 239 to rotate switch brushes the same as 212 to 215 inclusive. The magnet windings the same as 210 are connected to the straps associated with the contacts of relay 239. The terminals of the various switches are strapped together as shown on terminals 201 to 204 inclusive. In this manner all idle switches of a link group are simultaneously rotated to hunt for the switch terminals associated with the jack which has been actuated by the insertion of a plug. Since terminals 201 to 204, inclusive, are one set of a plurality of sets of like terminals, the brush members rotate until brush 215 encounters terminal 204. A circuit is thus established to energize relay 211 over a circuit from grounded battery through its right winding, brush 215, terminal 204, resistance 205, left inner normal contact of relay 206 to ground through the upper contact of jack 207. The operation of relay 211 opens the energizing circuit for switch magnet 210 and thus arrests the movement of the switch brushes. The operation of relay 211 further establishes an energizing circuit for relay 216 from grounded battery through the contact of relay 211, winding of relay 216, left winding of relay 211, brush 215 and thence to ground at the upper contact of jack 207. It will be noted that the right winding of relay 211 is in multiple with its left winding and the winding of relay 216 and thus the total resistance of the circuit is reduced to a point where terminal 204 is maintained busy to other switch brush members in connecting links the same as shown in Fig. 2. The reduction in the resistance of this circuit further establishes a shunt to release relay 208.

The operation of relay 216 establishes an energizing circuit for switch magnet 217 from grounded battery through its windings, right inner contact of relay 216 to

ground through the normal contact of relay 218. The energization of switch magnet 217 rotates brushes 219 to 222, inclusive, over the contacts of its bank in search of an idle 5 sender. When an idle sender is selected, a circuit is established from grounded battery through the left upper contact of sequence switch cam 401, winding of relay 402, terminal 257, brush 222, left winding of relay 10 218 to ground through the right outer contact of relay 216. Relays 218 and 402 are operated in the circuit traced. The operation of relay 218 opens the energizing circuit for switch magnet 217 and thus arrests the movement 15 of switch brushes 219 to 222. The operation of relay 218 further establishes an energizing circuit for relay 223 from ground through its contact, winding of relay 223, right winding of relay 218, brush 222, 20 terminal 257, winding of relay 402 to grounded battery through the left upper contact of sequence switch cam 401. It will be noted that the circuits through the left and right windings of relay 218 are in multiple 25 and thus the total resistance in series with brush 222 is reduced to maintain the sender busy. The operation of relay 223 connects brushes 219, 220 and 221 from the sender to the link circuit.

30 The operation of relay 402 as previously described establishes a circuit to energize the sequence switch magnet 400 from grounded battery through its winding, right upper contact of sequence switch cam 403 to ground 35 through the right outer contact of relay 402. The energization of magnet 400 rotates the sequence switch from position 1 to position 2 under the control of the circuit traced and to position 3 under the control of its 40 master contact 404. A circuit is now established to operate relay 405 from ground through the winding of relay 224, left outer contact of relay 223, brush 221, terminal 256, left and right winding of relay 405, right 45 middle contact of relay 402 to grounded battery through the right upper contact of sequence switch cam 401. Relay 224 does not operate in the circuit traced on account of the high resistance of the right winding of relay 405. The operation of relay 405 establishes a locking circuit for relay 402 which may be traced from grounded battery through the right outer contact of relay 405, right hand contact and winding of relay 402, 50 thence to ground over the operating circuit for relay 402 as previously traced. The operation of relay 405 further establishes circuits from the brushes 219 and 220 to the sender apparatus.

55 Two circuits are now established to the key-set illustrated in the lower portion of Fig. 2. One is traceable from ground through the windings of relays 406, 407 and 408, coil 460, lower contact of sequence switch cam 409, left contact of relay 405, ter-

60 minal 254, brush 219, right contact of relay 223, right inner normal contact of relay 224, brush 212, terminal 201, left middle normal contact of relay 206, conductor 225, right contact of relay 227 which is operated upon 70 the depression of any one of the keys in the key-set as hereinafter described. Upon the operation of relay 227 the circuit is extended from the right contact of relay 227 to the upper contact of a depressed key, to battery, 75 the potential and polarity of the battery being dependent upon the key depressed. The other circuit extends from ground through the windings of relays 410 and 411, lower contact of sequence switch cam 412, right 80 inner contact of relay 405, terminal 255, brush 220, left inner contact of relay 223, left inner contact of relay 224, brush 213, terminal 202, left outer normal contact of relay 206, conductor 226, left inner normal 85 contact of relay 227, winding of relay 228 to grounded battery. Relay 228 operates in the circuit traced and establishes an obvious circuit to light lamp 229, which indicates to the operator that the link or connector circuit is associated with an idle 90 sender.

95 The operator upon observing the lamp signal 229 depresses certain keys in accordance with the wanted line thereby associating heavy or light positive and negative potential with the contacts of relay 227 connected to conductors 225 and 226 in accordance with the key depressed. Let it be assumed that the number of the wanted line in the desired exchange is 2856. The operator depresses the digit key 2 thereby connecting light negative battery from conductor 230 through the lowermost upper contact of key 2 to the right contact of relay 100 227. The operation of key 2 further associates a heavy negative battery from conductor 231, lower contact of key 2 to the left inner contact of relay 227. The contact 105 234 of key No. 2 closes after the outer contacts have closed thereby completing a circuit for the operation of relay 227 from grounded battery through contact 234, winding of relay 227 to ground. The relay 227 110 operates and connects conductors 225 and 226 to the contacts associated with key 2 as previously described and circuits are completed over conductors 225 and 226 to operate relays as hereinafter described. At its 115 left inner contacts, relay 227 opens the energizing circuit for relay 228 to cause its release and extinguish lamp 229. This is incidental in the operation of the circuit and does not serve as an indication to the operator. The operation of relay 227 further 120 establishes a circuit to light lamp 235 from ground through its left outer contact, filament of lamp 235 to grounded battery. The lighting of lamp 235 indicates that the operator has properly actuated the key. The 125 130

operation of relay 227 and the illumination of lamp 235 consume sufficient time to insure the operation of the sender apparatus.

As previously described, the sender relays 410 and 411 are in series with conductor 226 and relays 406, 407 and 408 are in series with conductor 225 extending to the key set. After the digit key 2 is depressed and heavy negative battery associated with conductor 226, the relays 410 and 411 both energize as previously described. Light negative battery is connected to conductor 225 and on account of the high resistance in series with this circuit, relay 407 only is operated. The relay 406 does not receive sufficient current to energize and relay 408 is polarized to operate only when positive potential is associated with this conductor.

It will be remembered that the sequence switch 400 of the sender circuit is resting in position 3. When the sequence switch arrived in this position, a circuit was established to energize relay 413 from ground through the normal contact of relay 407, winding of relay 413, to grounded battery through the left lower contact of sequence switch cam 414. Upon the operation of relays 410 and 411, a circuit is established to energize relay 416 from ground through the left contact of relay 413, contact of relay 411, upper contact of sequence switch cam 415, winding of relay 416, to grounded battery through the upper contact of sequence switch cam 414. A similar circuit is established to energize relay 417 from ground through the left contact of relay 413, contact of relay 410, upper contact of cam sequence switch 479, winding of relay 417 to grounded battery through the upper contact of sequence switch cam 414. Upon the operation of relay 407, the energizing circuit for relay 413 is opened. This relay however does not immediately release and a circuit is established to operate relay 433 from grounded battery through the upper contact of sequence cam 414, winding of relay 433, upper contact of sequence switch 429, right contact of relay 413, to ground through the contact of relay 407. Relay 413 is slow to release and does not deenergize until relays 433, 416 and 417 have operated and established a locking circuit. This locking circuit may be traced from grounded battery through their windings and right inner contacts to ground.

The energization of any of the relays 416, 417, etc., establishes a circuit for energizing the sequence switch magnet 400 to move it from position 3 to 4. This circuit may be traced from grounded battery through its magnet winding, left upper contact of sequence switch cam 421 to ground through the middle contact of relays 416, 417, etc. The energization of relays 416 and 417 further establishes circuits to energize switch

magnets 426 and 427. The energizing circuit for switch magnet 426 may be traced from grounded battery through the left upper contact of sequence switch cam 428, resistance 470, windings and associated contact of magnet 426, brush 424, terminal 422 to ground through the right outer contact of relay 416. The energizing circuit for magnet 427 is traceable over a similar path from grounded battery through the left lower contact of sequence switch cam 428 which is effective upon the arrival of the sequence switch in position 5. Switch 426 advances from its normal position to position 1 and switch 427 remains in its normal position. The terminals associated with switch brush 424 are cross-connected, as indicated by numbers, to the outer, inner and middle contacts of relays 416, 417, 480, 433 and 434 that are normally associated with the armatures of said relays. Therefore, if terminal 1 is cross-connected to the middle contact of relay 480 and terminal 2 is cross-connected to the middle contact of relay 417 a circuit is established to energize magnet 426 in position 1 and rotate brush 424 to position 2. The operation of relay 417 disassociates ground from terminal 2 and thus the switch is arrested in its rotary movement upon the association of its brush with said terminal. It is thus apparent that such cross connections may be made and such of the relays operated to rotate brush 424 automatically to any position in its bank dependent upon the particular combination of relays in the chain which are energized upon the depression of the digit key.

Let it be assumed that the operator depresses key 8 for the second digit of the desired number in the manner described for the depression of key 2. Light negative battery is now connected to the conductor 225 and no potential is associated with conductor 226. The application of the light negative battery to conductor 225 establishes an operating circuit for relay 407 as previously described. The remaining relays 406 and 408 in the chain again do not operate. As previously described, relay 413 is operated during the released period of relay 407. The operation of relay 407 opens the energizing circuit for relay 413. It however remains operated momentarily to establish an energizing circuit for relay 430 which may be traced from grounded battery through the right lower contact of sequence switch cam 414, winding of relay 430, lower contact of sequence switch cam 429, right contact of relay 413 to ground through the contact of relay 407. The operation of relay 430 establishes a locking circuit for itself to ground through its right inner contact. The operation of relay 430 further removes the ground circuit from terminal 120

No. 8 associated with brush 431. The magnet 432 is energized from grounded battery through the right upper contact of sequence switch cam 428, resistance 471, winding and 5 associated contact of switch magnet 432, brush 431 and its associated contact in its normal position to ground through the right outer contact of relay 430. The switch now rotates over its associated contacts until 10 it is associated with terminal 8 which is opened at the middle contact of relay 430. Since the switch magnet no longer has an energizing circuit at position 8, the brush 431 is arrested in its rotary movement. The 15 energization of relay 430 further establishes a circuit for the energization of sequence switch magnet 400 from grounded battery through its winding, right upper contact of sequence switch cam 421 to ground through 20 the middle contact of relay 430. When the sequence switch 400 rotates out of position 4 the locking circuit for relays 416, 417 and 433 is opened at the upper contact of cam 414 to cause the deenergization of these 25 relays.

The depression of the next digit key No. 5 is now effective and associates heavy positive potential with conductor 225 and no potential with conductor 226. The heavy 30 positive potential establishes an operating circuit for relays 406, 407 and 408 which operate in series with conductor 225. Circuits are now established to operate relays 434, 433 and 480 of the upper chain of relays. The energizing circuit for relay 480 35 may be traced from grounded battery through the upper contact of sequence switch cam 414, winding of relay 480, upper contact of sequence switch cam 475, contact of relay 406 to ground through the left contact of relay 413. The operation of relay 433 is from the same battery source through its winding, upper contact of sequence switch cam 429, right contact of relay 413 to 40 ground through the contact of relay 407. The energizing circuit for relay 434 is from the same battery source through its winding, upper contact of sequence switch cam 476, contact of relay 408 to ground through the 45 left contact of relay 413. The stepping magnet 427 controlling the brush 425 is now energized from grounded battery through the left lower contact of sequence switch cam 428, resistance 473, winding and associated contact of magnet 427, brush 425 and its 50 associated contact in its normal position to ground through the outer contacts of relays 434, 433 and 480. Switch magnet 427 is continuously energized as brush 425 is associated with contacts characterized by ground through the contacts of the relays. The cross connections are such that brush 55 425 rotates to the fifth contact which is open and the rotary movement of the brush is arrested. The energization of relays 480, 433 and 434 further establishes an energizing circuit for sequence switch magnet 400 from grounded battery through its winding, left upper contact of sequence switch cam 421 to ground through the middle contact of said 60 relays. The sequence switch is thus rotated from position 5 to position 6 and upon the rotation of the sequence switch out of position 5 the locking circuit for relay 430 in the lower chain is opened thus causing its 65 release.

The fourth digit key depressed by the operator is key No. 6 thereby associating light positive potential with conductor 225 to operate relays 407 and 408. The operation of 70 these relays establishes a circuit to operate relay 420 of the lower chain and the operation of relay 420 removes ground from contact No. 6 in the bank of the fourth digit switch associated with brush 436. The energizing circuit for relay 420 may be traced from grounded battery through the right lower contact of sequence switch cam 414, winding of relay 420, lower contact of sequence switch cam 476, contact of relay 408 75 to ground through the left contact of relay 413. The energizing circuit for magnet 435 may be traced from grounded battery through the right lower contact of cam 428, resistance 472, winding and associated contact of magnet 435, brush 436 and its associated contact in its normal position to ground through the outer contact of relay 420. Brush 436 is thus rotated from its 80 normal position to position 1 and continues to rotate upon its association with each contact that is characterized by ground from the normal contacts of the lower chain of relays. The operation of relay 420 further establishes a circuit to energize sequence 85 switch magnet 400 which may be traced from grounded battery through its winding, right upper contact of cam 421 to ground through the middle contact of relay 420.

Brush 439 is assembled upon the same 90 switch bank as brush 424 and rotates an equal number of positions. In a like manner, brush 451 is associated with brush 431, brush 452 associated with brush 425 and brush 453 with brush 436. Thus in position 95 7 of the sequence switch, the counting relays are associated through brush 439 and thence through the upper contacts of sequence switch cam 477 to ground on the contact of relay 437 which operates during the 100 upward movement of a retractive impulse automatic switch. The register or digit switches now remain positioned awaiting the selection of an outgoing trunk leading to the exchange designated by the jack into 105 which the operator has inserted the plug. The selection of a trunk is purposely not effective until after four digits of the called number have been recorded and the sequence switch 400 moved into position 110 7. 115

In this way the trunk is not held busy unnecessarily during the registration of the wanted line designation, as would otherwise be the case if the selection occurred simultaneously with the selection of the jack.

Upon the rotation of the sequence switch to position 7 in the manner described, the high resistance winding of relay 405 is short circuited at the lower contact of sequence switch cam 401. The circuit path for this shunt circuit is apparent and need not be described. It will be remembered that a circuit is established through the winding of relay 224 and the windings of relay 405 to operate relay 405 but on account of the high resistance of the right winding of relay 405, relay 224 does not operate. The shunt of the high resistance winding of relay 405 now establishes a low resistance circuit which allows sufficient current to flow through the winding of relay 224 to cause its operation. The operation of relay 224 establishes a circuit to operate relay 228 from grounded battery through its winding, left inner normal contact of relay 227, conductor 226, left outer normal contact of relay 206, terminal 202, brush 213, left inner contact of relay 224, left outer normal contact of relay 246 to ground through the segments of interrupter 265. Relay 228 is now repeatedly operated and released through the contacts and segments of the constantly rotating interrupter 265. Each operation of relay 228 establishes a circuit to light lamp 229 to indicate to the operator that the sender register switches have been set in response to the operation of the digit keys. The operation of relay 224 further establishes an energizing circuit for switch magnet 240 from grounded battery through its windings, left outer contact of relay 224, right outer normal contact of relay 246 to ground through the normal contact of relay 241. Brushes 242 to 245, inclusive, are now rotated over the contacts of its bank in search of an idle trunk leading to the desired exchange. An idle trunk is characterized by grounded battery associated with terminal 253. When brushes 242 to 245 are rotated to the position of an idle trunk, an energizing circuit is established for relay 241 traceable from grounded battery through resistance 308, right normal contact of relay 300, left outer normal contact of relay 301, terminal 253, brush 245, left winding of relay 241 to ground through the right outer contact of relay 224. The operation of relay 241 opens the energizing circuit or switch magnet 240 and thus arrests the rotary movement of its associated brush members. The operation of test relay 241 further establishes a circuit to energize relay 246 from ground through its contact, right windings of relays 246 and 241 and thence to grounded battery over the operating circuit for relay 241. It will be noted that the oper-

ating circuit for relay 246 is in multiple through the right winding of relay 241 with the operating circuit through the left winding of relay 241. The ohmic resistance of this path in series with brush 245 is thus reduced in order that terminal 253 may be held busy to other link circuits seeking an idle trunk. This busy shunt remains associated with terminal 253 and brush 245 until relay 300 is operated to disassociate battery potential from terminal 253. The operation of relay 246 further establishes a locking circuit for itself and an energizing circuit for relays 300 and 206 from grounded battery through the winding of relay 300, terminal 252, brush 244, left winding and left inner contact of relay 246, brush 214, terminal 203, winding of relay 206 to ground through the upper contact of jack 207.

The operation of relay 206 opens at its left inner contact the energizing circuits for relays 211 and 216 to cause their release. The operation of relay 300 opens the energizing circuit for relay 241 to cause its release. The circuit for the stepping magnet 240 is held open at the contacts of relay 246. The operation of relay 300 further establishes an obvious circuit to operate relay 301 which locks through its left inner contact to grounded battery through the contact of relay 302.

A trunk to automatic switches in a distant exchange such as indicated in Fig. 3 has now been selected and prepared for operation as directed by the sender circuit shown in Fig. 4. As previously stated, the automatic switching apparatus at the distant exchange may be of the revertive impulse type, of the same general structure as shown in detail in Patent No. 1,403,861 issued January 17, 1922, to A. E. Lundell. Associated with an automatic switch of this type is a commutator diagrammatically indicated at 305. Upon the energization of the switch to select an idle terminal commutator 305 is rotated over the contact 309 to release the stepping relay 437 which is operated over a fundamental circuit hereinafter described. The energization of relay 246 establishes this fundamental circuit to energize the automatic switch and operate certain of the counting relays shown in Fig. 5. This fundamental circuit may be traced from grounded battery through the winding of relay 304, contact of sequence switch cam 312, terminal 251, brush 243, right inner contact of relay 246, left inner contact of relay 223, brush 220, terminal 255, right inner contact of relay 405, upper contact of cam 412, left normal contact of relay 438, winding of stepping relay 437, upper contact of sequence switch cam 409, left contact of relay 405, terminal 254, brush 219, right contact of relay 223, left middle contact of relay 246, brush 242, terminal 250 to ground.

through the contact of sequence switch cam 314. The relay 304 at the automatic exchange and stepping relay 437 at the sender are both operated upon the establishment of the fundamental circuit. The operation of relay 304 causes the selector switch to advance for brush selection. During this operation the conducting and non-conducting segments of interrupter 305 are associated with its contacts whereby ground is connected intermittently to the conductor 307 of the selector switching circuit. Each association of the conducting portion of commutator 305 with contact 309 establishes a shunt circuit around the winding of relay 437 to cause its release.

It will be remembered that the first register switch is set to associate brushes 424 and 439 with the contact terminals in position 2. Upon the operation of relay 437, a circuit is established to operate counting relay 441 traced from ground through the contact of relay 437, upper contacts of sequence switch cam 477, brush 439 and its associated contact, contact of counting relay 440, winding of relay 441 to grounded battery. The operation of relay 441 establishes an energizing circuit for relay 440 which is effective upon the release of relay 437 which occurs when interrupter 305 associates ground with conductor 307. The operating circuit for relay 440 may be traced from grounded battery through the windings of relays 441 and 440 in series, contact of relay 441 to ground through the contact of sequence switch cam 450. The operation of relay 440 associates brush 439 with the winding of counting relay 443 which energizes upon a subsequent energization of stepping relay 437 over a circuit the same as the energizing circuit traced for relay 441 with the exception that it is carried through the normal contact of relay 442 and the contact of relay 440. Upon a subsequent release of relay 437, an energizing circuit is effective for relay 442 which operates to establish a circuit for relay 445. A subsequent operation of relay 437 energizes relay 445 and its release removes the shunt from relay 444 which operates and establishes an obvious circuit to energize the winding of relay 438. The operation of relay 438 opens the fundamental circuit and thus causes the release of relay 304 upon the rotation of interrupter 305 to a non-conducting segment. The release of relay 304 opens the energizing circuit for the selector switch drive and thus arrests its movement. The operation of relay 438 further establishes a circuit to energize sequence switch magnet 400. This circuit may be traced from grounded battery through the winding of sequence switch magnet 400, lower contact of sequence switch cam 421 to ground through the right contact of relay 438. The

sequence switch is thus rotated from position 7 to position 8. In this position of the sequence switch, the locking circuit for the counting relays is opened to cause their release. The release of counting relay 444 ⁷⁰ opens the energizing circuit for relay 438 to cause its release. Upon the release of relay 438, a circuit is established to energize sequence switch magnet 400 to rotate the sequence switch from position 8 to position 9. ⁷⁵ This circuit may be traced from grounded battery through the winding of sequence switch magnet 400, lower contacts of sequence switch cam 478 to ground through the left normal contact of relay 438. ⁸⁰

In sequence switch position 9, the fundamental circuit is again established to further control the switches at the automatic exchange. It will be noted that in position 9, brush 451 is associated with the contact of stepping relay 437 through the lower right and upper left contacts of sequence switch cam 477. Upon the energization of the switch at the automatic exchange the counting relays are operated in the manner previously described until the fundamental circuit is again opened at the contact of relay 438. ⁸⁵ ⁹⁰

Other switches at the automatic exchange ⁹⁵ operate in the manner indicated in response to the various digits set upon the registers of the sender circuit and the counting relays operate under the control of brushes 452 and 453 in positions 11 and 13 of the sequence switch 400. ¹⁰⁰

Upon the completion of the control of switches at the automatic exchange, the sequence switch 400 is rotated from position 13 by the operation of relay 438 and is restored to normal under the control of its master contact 404. Upon the rotation of the sequence switch out of position 13, the energizing circuit for relay 405 is opened at the lower contact of sequence switch cam 401. The release of relay 405 opens the circuit paths extending to the sender and opens the locking circuit for relay 402 to cause its release. During the rotation of the sequence switch from position 14 to position 1, circuits are established from grounded battery through the contacts of sequence switch cam 428, resistance 470, 471, 472 and 473, windings of the register switch magnets to ground through the normal contacts of the relays of the upper and lower combinations including relays 417 and 420. The sender register switches are thus restored to their normal positions. The energizing circuit for relay 224 is opened at the sequence switch cam 401 and releases at the same time as relay 405. The release of relays 405 and 402 opens the energizing circuit for relays 218 and 223 to cause their release. The release of relay 224 establishes the talking circuit through its normal contacts from a dis- ¹¹⁰ ¹¹⁵ ¹²⁰ ¹²⁵ ¹³⁰

tant exchange to the tip and ring conductors of jack 207 and thence through the cord circuit 263 to the calling subscriber. The release of relay 223 disconnects the conductors extending to brushes 219, 220 and 221 from the talking circuit. During the period of time that the talking circuit is held by the subscriber relays 246 and 206 are the only relays energized.

Upon the completion of a conversation, the operator at the A switchboard is notified by the usual supervisory signal and removes plugs 261 and 260 from the jacks. The removal of plug 261 from jack 207 opens the energizing circuit for relays 206 and 246 at the manual office and relay 300 at the automatic office which thereupon deenergize. The switch and associated circuits at the automatic office restore to normal in the usual manner.

What is claimed is:

1. In a telephone exchange system in which incoming lines to a manual exchange are extended to an automatic exchange over outgoing trunks, said automatic exchange being represented at said manual exchange by a plurality of sets of terminals, an operator's position, means at said operator's position for interconnecting an incoming line and one of said sets of terminals, a common switching device for selecting an idle one of said trunks and said interconnected terminals, means responsive to the interconnection of said line with a set of terminals to actuate said switching device, and other means at said operator's position for variably controlling the apparatus of said automatic exchange over said selected trunk.

2. In a telephone exchange system in which incoming lines to a manual exchange are extended to a plurality of automatic exchanges over outgoing trunks, said automatic exchanges being represented at said manual exchange by a plurality of sets of terminals, operators' positions, means at said operators' positions for interconnecting incoming lines and any of said sets of terminals, a plurality of senders adapted to control the apparatus at said automatic exchanges, a common switching device for selecting an idle sender, an idle trunk to a desired exchange and an interconnected set of terminals, means whereby said interconnection of a line with a set of terminals actuates said switching device, and means for actuating a selected sender.

3. In a telephone exchange system, in combination, lines incoming to a manual office, outgoing trunks extending to switches at an automatic office, an operator's position, a plurality of jacks at said operator's position, a cord circuit for interconnecting an incoming line and any one of said jacks, a plurality of variably operable senders, a common switching device for selecting an idle

sender, an idle trunk and an interconnected jack, means whereby the interconnection of a line with a jack by said cord circuit actuates said switching device, and means to actuate a selected sender to control the switches at an automatic office over the selected trunk and connect thereto said interconnected jack.

4. In a telephone exchange system, in combination, lines incoming to a manual office, outgoing trunks extending to an automatic office, an operator's position, a plurality of jacks at said operator's position, a cord circuit for interconnecting an incoming line and any one of said jacks, a plurality of senders, a common switching device for selecting an idle sender, an idle trunk and an interconnected jack, means whereby the interconnection of a line with a jack by said cord circuit actuates said switching device, a calling device adapted to be set in accordance with the designation of a desired line for controlling a sender, and means to connect said calling device with said selected sender.

5. In a telephone exchange system, in combination, lines incoming to a manual office, an operator's position, a plurality of jacks at said operator's position, a cord circuit for interconnecting an incoming line with any one of said jacks, a plurality of senders, a common switching device for selecting an idle sender, an idle trunk and an interconnected jack, means whereby the interconnection of a line with a jack by said cord circuit actuates said switching device, a calling device adapted to be set in accordance with the designation of a desired line for controlling said sender, means to connect said calling device with said selected sender, and other means for disconnecting said calling device in order that it may be connected to others of said plurality of senders.

6. In a telephone exchange system, comprising an operator's position, a plurality of jacks accessible to the operator at said position, a common group of outgoing trunks and a common group of senders, a link circuit comprising three switches, one of said switches being adapted to select an individual jack at said operator's position, a second switch to select an idle one of said senders, and a third switch to select an idle one of said trunks, and means at said operator's position to actuate said link.

7. In a telephone exchange system, in combination, lines incoming to a manual office, outgoing trunks extending to an automatic office, an operator's position, a plurality of jacks, a cord circuit for interconnecting an incoming line and any one of said jacks, a plurality of register senders, a link circuit comprising three switches, one of said switches being adapted to select an interconnected jack, a second switch to select an idle

sender, and a third switch to select an idle trunk, means whereby the interconnection of a line with a jack by said cord circuit actuates said link, a calling device adapted to be set in accordance with the designation of a desired line for setting the registers of said selected sender, and means to prevent the selection of an idle trunk until the registers of a selected sender are completely set.

8. In a telephone exchange system, in combination, lines incoming to a manual office, outgoing trunks extending to an automatic office, an operator's position, a plurality of jacks, a cord circuit for interconnecting an incoming line and any one of said jacks, a plurality of register senders, a link circuit comprising three switches, one of said switches being adapted to select an interconnected jack, a second switch to select an idle sender and a third switch to select an idle trunk, means whereby the interconnection of a line with a jack by said cord circuit actuates said link, a calling device adapted to be set in accordance with the designation of a desired line for setting the registers of a selected sender, means to prevent the selection of an idle trunk until the registers of a selected sender are completely set, a signal, means to operate said signal in one manner to indicate that the trunk selecting switch is in operation, and means to operate said signal in a different manner to indicate

that said trunk selecting switch is unable to find an idle trunk.

9. In a telephone exchange system, in combination, lines incoming to a manual office, outgoing trunks extending to switches at an automatic office, an operator's position, a plurality of jacks at said operator's position, a cord circuit for interconnecting an incoming line and any one of said jacks, a plurality of variably operable senders, a plurality of common switching devices each comprising three switches, one of said switches being adapted to select an individual jack at said operator's position, a second switch to select an idle one of said senders and a third switch to select an idle one of said trunks, means whereby the interconnection of a line with a jack by said cord circuit actuates the idle ones of said plurality of switching devices, means operable through the selection of an interconnected jack by said jack selecting switch to arrest the movement of the jack selecting switches in all of said plurality of switching devices, means actuated upon the selection of said jack to select an idle sender, means to select an idle trunk and means in said sender to actuate said trunk selecting means.

In witness whereof, I hereunto subscribe my name this 12th day of December, A. D., 1924.

GERALD DEAKIN.
